CONTAINER CLOSURE

George E. Bennett, San Mateo, Calif.

Application April 27, 1935, Serial No. 18,525

8 Claims. (Cl. 215—46)

My invention relates to container closures, and more particularly to improvements in demountable container caps.

It is among the objects of my invention to provide a cap construction embodying means for readily loosening the cap prior to its removal.

Another object of my invention is to provide means by which the cap may be loosened without damaging the cap or impairing its utility as a subsequent closure for the container.

A further object of my invention is to provide a closure comprising a sealing disk and a cap for securing the disk in place, in which means are provided for locking the disk into the cap upon its first application so that subsequently the closure may be handled as a unit.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

Figure 1 is a vertical sectional view showing portions of a container closure embodying my invention. This view shows the arrangement of the parts just prior to the final screwing down of the cap and before the sealing disk is expanded into interlocking engagement with the cap.

Figure 2 is a plan view of the closure after the sealing disk has been expanded, portions of the structure being broken away to disclose the construction more clearly; and

Figure 3 is a fragmentary vertical sectional view of the same.

Figure 4 is a fragmentary vertical sectional view of the closure after the spacing element has been removed.

Figure 5 is a fragmentary vertical sectional view of a closure embodying a modified form of structure, and shows the arrangement of parts before the sealing disk is expanded; and

Figure 6 is a plan view of the same after the sealing disk has been expanded into interlocking engagement with the cap, portions of the structure being broken away to disclose the construction more clearly.

Figure 7 is a plan view of a container closure embodying another modified form of structure, portions of the structure in this view also being broken away to disclose the construction more clearly.

In terms of broad inclusion, the container closure embodying my invention comprises a cap

for the container and a sealing disk interposed between the cap and container. Means are provided for locking the sealing disk to the cap, and a spacing element is also preferably provided between the cap and disk and mounted for removal independently of the cap. By locking the sealing disk to the cap, the disk will come off simultaneously with the removal of the cap; and the separately removable spacing element operates to loosen the cap so that it may easily be removed from the container.

In greater detail, and referring particularly to Figures 1 and 2, a form of closure embodying my invention comprises a cup-shaped cap 2 preferably of metal and preferably threadably mounted on a container 3. An aperture 4 is formed in the top of the cap 2, providing an opening bounded by an annular flange 6. A sealing disk 7 of suitable material, such as metal, is interposed between the cap 2 and container 3.

Means are provided for loosening the cap prior to its removal. As best shown in Figure 2, this means comprises a piece of wire shaped to provide an annular ring portion 8 overlying the sealing disk 7 under the cap flange 6. A series of loops 9 are preferably formed in this ring to space the latter from the cap. One end of the wire extends out from under the edge of the cap flange 6; and is formed to provide a finger hold 11, lying in the plane of the spacing ring 8, so that this finger hold normally lies slightly above the sealing disk 7, in which position it is readily grasped. When it is desired to remove the spacing element it is only necessary to lift up the finger hold and pull the wire out from under the flange 6. This loosens the cap so that it may easily be removed.

When a container is first packed the cap is screwed down tightly to effect the desired bearing pressure against the sealing disk. The firmness with which this cap is applied makes it difficult if not impossible to unscrew the cap by hand, and often necessitates the use of special tools and may involve destroying the cap. In my improved closure the removal of the spacing element relieves the bearing pressure and loosens the cap so that it is easily removed by hand. After the first opening the spacing element may be discarded since the remaining elements of the structure, namely, the cap and sealing disk, provide a complete closure for reclosing the container.

Means are also preferably provided for locking the sealing disk 7 to the cap 2 so that the two parts will come off as a unit when the cap is unscrewed. In the type of cap shown, the seal-

ing disk 7 is made separately from the cap, and unless means are provided for locking the disk to the cap the disk has to be removed after the cap is taken off. To remove such a disk it becomes necessary to apply a prying tool, such as a knife, under the edge of the disk. This involves additional time and trouble and often results in bending or otherwise ruining the disk, so that it is useless, or less useful, for reclosing the container.

In my improved construction, the peripheral portion of the sealing disk 7 is formed to provide an upstanding ridge or bead 12. This raised bead overlies the rim of the container 3 and provides a groove in which the gasket 13 of rubber or other conformable material is disposed. The bead 12 also serves another function arising out of its flattening out under the pressure of the cap. In other words, the ridged peripheral portion 12 of the disk provides an expandible ring which flattens and is extended out radially under the cap pressure. Figures 2 and 3 show the closure tightly sealed, the disk being expanded; and Figure 1 shows the arrangement of parts prior to expansion. In order to facilitate the expansion a series of radially extending slots or notches 14 may be cut in the periphery of the disk. The provision of these slots permits the ridged portion 12 to flatten out with less applied pressure, and is especially desirable if a heavier sealing disk is employed.

The locking of the sealing disk to the cap is facilitated by the provision of an annular recess 15 in the cap and disposed circumferentially of the disk. By this construction the edges of the expansion ring 12 will be forced out into the recess 15, so that a positive interlocking engagement is effected between the disk and cap to provide a unitary structure for handling. When the cap is subsequently removed the sealing disk will be taken off with it and permanently held within the cap as a functionally integral unit. The sealing disk and cap then provides a complete closure, as shown in Figure 4, for the convenient reclosing of the container.

Figures 5 and 6 show a modified form of cap, in which the peripheral portions of the sealing disk 16 are provided with concentric corrugations 17. The outside diameter of the disk is such that it may be inserted in the cap by the use of some slight pressure. The small degree of expansion of the disk due to the flattening of the corrugation which occurs when the cap is screwed down hard, is sufficient to interlock the peripheral edge of the disk in the cap recess 18. In this construction the rubber or other conformable material for the gasket is disposed in the concentric grooves provided by the corrugations. By the concentric arrangement of the gasket holding grooves, each outer ring of the gasket tends to supplement the seal provided by an inner ring. Such an arrangement improves the seal and also reduces the amount of gasket material required.

A modified form of spacing element is also shown. In this case, the ring portion 19 is bent in zig-zag formation to give width to the ring. The flat loops thus provided will overlie the corrugations of the expansion ring without dropping into the groove between the corrugations, and also function to hold the spacing element away from the cap 2. A finger hold 21 is also formed at one end of the wire; and this hold

is normally slightly above the sealing disk 16 and under the cap aperture 4.

Another variant form of my closure construction is shown in Figure 7. In this case the spacing element comprises a piece of relatively stiff wire bent in the form of a ring, adapted to overlie the peripheral portions of the sealing disk 22 under the annular flange 23 of the cap 24. The wire is formed with a series of offset portions 26 connected by smoothly curved portions 27. At the inner end 28 of one of the curved portions the wire extends out from under the edge of the cap flange 23, so that any suitable point such as a fork tine, may be engaged between the wire and the edge of the cap flange.

By forcing the tool around the inner edge of the flange the stiff wire ring is wedged out from under the flange. The drawing out of the spacing ring in this manner is facilitated by the smoothly curved portions 27 of the ring, as will be readily understood. The offset 26 gives width to the ring and functions to space the ring away from the cap. Because the total closing pressure, which is considerable, is distributed over the whole length of the spacing element, the unit pressure on a short length of the wire is so small that it disengages from under the flange very readily.

Of course it is understood that any of the types of spacing elements shown may be used either with or without the sealing disk locking feature. A great advantage of my removable spacing elements is that they normally lie within the limits defined by the cap. No part of the spacing element extends outside the cap to detract from its compactness or appearance.

Referring particularly to the interlocking of the two parts of the closure, it is understood that the pressure of applying the cap may be relied upon to expand the disk into interlocking engagement with the cap; or this expansion may be effected by other pressure means prior to the application of the cap to a container. In this case, since unlimited pressure for assembling by machine is available, the disk may be materially larger in diameter than it would be possible to push into the cap by hand assembly. When machine assembled the peripheral corrugations permit a resilient contraction of diameter of the disk as it is forced past the throat or narrow portion of the cap just below the annular recess 15.

I claim:

1. A container closure comprising a cap for the container, a sealing disk interposed between the cap and container, and means expandible as the cap is applied thereto for permanently locking the sealing disk to the cap.

2. A container closure comprising a cap for the container, a sealing disk interposed between the cap and container, and means integrally formed with the disk and expandible under the pressure of the cap for locking the sealing disk to the cap when the latter is applied to the container.

3. A container closure comprising a cap for the container, and a sealing disk interposed between the cap and container and having a notched and grooved peripheral portion providing an expansion ring expandible by pressure for permanently locking the disk to the cap.

4. A container closure comprising a cap for the container, and a sealing disk interposed between the cap and container and having a corrugated peripheral portion providing a ring ex-

- pendible by pressure as the cap is applied over the disk for permanently locking the disk to the cap.
5. A container closure comprising a cap for the container, a sealing disk interposed between the cap and container and having a grooved peripheral portion providing a ring expandable by pressure as the cap is applied over the disk for permanently locking the disk to the cap, and a 10 gasket in said groove.
6. In a container closure, a sealing disk having concentric peripheral corrugations to permit change in diameter, and a cap for applying the disk having an annular recess in which the disk is locked by expansion of the disk as the cap is applied thereover.
- 15 7. A container closure comprising a cap for the
- container, and a piece of wire interposed between the cap and container to provide a spacing element and mounted for removal independently of said cap, said wire having loops therein for holding it away from sides of the cap.
8. A container closure comprising a cap for the container, a sealing disk having an expandable rim formed integrally with the disk for locking the disk within the cap, and a spacing wire interposed between the cap and the expandable rim 10 and adapted for removal through the cap top, said wire having loops therein for holding the body of the wire away from the sides of the cap and for distributing pressure over a major area of the rim.
